UNITED STATES PATENT OFFICE.

ALANSON BLANCHARD, OF ARLINGTON, MASSACHUSETTS.

CLOTHES-DRIER.

SPECIFICATION forming part of Letters Patent No. 326,836, dated September 22, 1885.

Application filed February 9, 1885. (No model.)

To all whom it may concern:

Be it known that I, ALANSON BLANCHARD, of Arlington, in the county of Middlesex, of the Commonwealth of Massachusetts, have 5 invented a new and useful Improvement in Clothes-Driers; and I do hereby declare the same to be described in the following specification and represented in the accompanying drawings, of which—

- 10 Figure 1 is a top view, Fig. 2 a side elevation, and Fig. 3 an end view, of a clothes-drier of my improved kind, the nature of my invention being duly defined in the claims herein-
after presented. Fig. 4 is a top view of the
15 forked bar or clothes-retainer to be described.
The said clothes-drier has two pairs of legs,
A, those of each pair being hinged or jointed
together at their upper ends and to a brace,
B, extending from them, as represented. The
20 two pairs of legs A are placed at a suitable
distance apart, and are connected by bars C
extended from each of the legs of one pair
to those of the other, in manner as repre-
sented. Each brace B, at its foot, is connected
25 with the ground or floor by a hinge or staple,
a, going through the brace and into the floor,
or into a short post driven into the ground.
A series of endless ropes, C', are applied to the
pairs of legs and the inclined braces, each of
30 such ropes being extended through all the legs
and both of the braces and tied together at
their ends, in consequence of which, on the
legs of each pair being simultaneously moved
away from each other, each of the ropes will
35 be drawn taut. Resting on each part of each
rope extending between the pairs of legs is a
bar, D, which is forked at each end in order
for it to receive and embrace the two legs, a
top view of such bar being shown in Fig. 4.
40 After clothes may have been hung on the rope
the forked bar is to be placed on them to keep
them thereon, it being used instead of clothes-
pins. When so arranged on the clothes, the
45 two legs between which such bar is extended.

Between one brace and the pair of legs im-
mediately connected to it, and depending from
such brace and legs, there is arranged a hanger,
E, which answers as a seat for a person to sit
upon, or as a support for a clothes-basket. 50
I usually form it of a rope rove through the
brace and both of the legs and tied together
at its ends, and having the parts that go be-
tween the legs and between them and the
brace curved or bowed downward and tied 55
together, so as to form a seat, which a person,
by straddling it, can sit upon, or can use to
support a clothes-basket when placed upon it.

The clothes-drier may be used to sustain a
hammock slung within it, or it may answer to 60
support a tent-cloth thrown over it.

When not intended for use, the clothes-drier
may have its braces and each of its pairs of
legs folded together, so as to reduce it to a
small compass, either for storage or transpor- 65
tation of it.

I claim—

1. The combination of the two pairs of legs
having those of each pair hinged together at
their upper ends with the two braces hinged 70
to said pairs, and with the series of ropes go-
ing through the legs and braces, all being
substantially as set forth.

2. The combination of the hanger E, extend-
ing between one of the braces and the next 75
contiguous pair of legs and depending there-
from, with the two braces and the two pairs of
legs, connected substantially as set forth.

3. The combination of the clothes-retainer
D, forked at its ends and applied to the legs 80
and rope extending between them, as set forth,
with the clothes-drier consisting of the two
pairs of legs, the inclined braces, and the ropes
or bars arranged with and applied to such
legs, as set forth.

ALANSON BLANCHARD.
